Primary Examiner — Mark Goodwin(74) *Attorney, Agent, or Firm* — Donald J. Ersler(57) **CLAIM**

The ornamental design for grapple jaws, as shown and described.

DESCRIPTION

FIG. 1 is a perspective view of grapple jaws retained by an actuation mechanism in a retracted orientation incorporating my new design;

FIG. 2 is a front elevation view of grapple jaws in a retracted orientation thereof;

FIG. 3 is a front elevation view of grapple jaws in a closed orientation thereof;

FIG. 4 is a left side view thereof;

FIG. 5 is a right side view thereof;

FIG. 6 is a top plan view thereof; and,

FIG. 7 is a bottom plan view thereof.

The dashed lines in FIGS. 1-7 are for illustrative purposes only and form no part of the claimed invention.
